UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

PICKER MECHANISM FOR ENVELOPE MACHINES AND THE LIKE.

Application filed August 12, 1921. Serial No. 491,762.

To all whom it may concern:

Be it known that I, WILLARD E. SWIFT, a citizen of the United States, residing at Worcester, in the county of Worcester and 5 Commonwealth of Massachusetts, have invented a new and useful Improvement in Picker Mechanism for Envelope Machines and the like, of which the following, together with the accompanying drawings, is 10 a specification.

My present invention relates to gumming or picker devices used in envelope machines and the like for applying adhesive to successive uppermost blanks of a stack, and for 15 removing said blanks, one by one, from said stack for presentation to the usual forwarding devices of the machine.

The invention relates especially to the action of the picker or gummer on that portion of the blank which eventually becomes the seal flap of the envelope; the object of the invention being to combine with the usual vertical movement of the seal flap gummer a horizontal or wiping movement, so 25 as to spread the adhesive thinly and evenly along the edge of the seal flap, thereby preventing the excessive deposit of moist adhesive and the consequent disadvantages of buckling and slow drying of the seal flap. 30 The invention resides in the novel combination and arrangement of instrumentalities hereinafter described in detail, reference being had to the accompanying drawings, in which—

Fig. 1 is a front view, partly in section, showing the invention applied at the gumming station of the ordinary envelope machine.

Fig. 2 is a fragmentary top plan view of 40 the parts shown in Fig. 1.

Fig. 3 is a side elevation of said parts, showing their relation to a stack of blanks in the machine.

Figs. 4 and 5 are fragmentary detail sectional views, in front and side elevation respectively, of the seal flap gumming device, showing the parts in the positions which they occupy in the first part of their cycle of operations.

Fig. 6 is a view similar to Fig. 5, but showing a change in the position of the parts as the picker or gummer descends.

Figs. 7 and 8 are views similar to Figs. 4

and 5, with the parts in the positions occupied when the seal flap gummer contacts 55 with the stack of blanks.

Fig. 9 is a diagrammatic view showing the initial contact of the seal flap gummer with the uppermost blank of the stack, corresponding to the position of the mechanism 60 shown in Figs. 7 and 8.

Fig. 10 is a fragmentary sectional view similar to Fig. 8, showing the final position of the seal flap gummer with relation to the stack.

Fig. 11 is a diagrammatic view similar to Fig. 9, corresponding to the position of the parts shown in Fig. 10.

Like reference characters refer to like parts in the different figures.

Referring first to Figs. 1, 2 and 3, the usual upper frame of an envelope machine of the reciprocating type is indicated at 1, said frame providing a bearing 2 for the vertical reciprocating picker rod 3. The latter has 70 secured to its lower end, in any suitable manner, a bar 4, extending horizontally and supporting, in the usual way, the rigid back flap or end flap gumming dies 5, 5. The bar 4 also provides support, in the manner hereinafter described, for a seal flap gumming die 6, and these several gumming dies are adapted to be supplied in the usual manner with moist adhesive by the traversing movements of gum transferring rollers 7 and 8, 80 the latter having supports 9, 9, which travel back and forth on rods 10, 10 on the fixed framework.

The gumming die 6 is suspended by a pair of rods 11, 11 from a head 12, the latter 90 adapted to slide in and out on the bar 4 which, for this purpose, is constructed with lateral tongues 13, 13 that enter undercut grooves of said head, as shown in Fig. 1. On opposite sides of the guideway thus 95 formed, the head 12 carries rearwardly projecting bolts or rods 14, 14, the heads 15 of which cooperate with a yoke 16, carried by bar 4, to limit the forward movement of the head 12. Compression springs 17, carried 100 by the rods 14, tend to force the head 12 outwardly or forwardly; this tendency is normally resisted by the engagement of rolls 18, 18, carried by head 12, with stationary overhanging members 19, 19, the inner edges 105 of which, engaged by the rollers 18, are in

2
the form of cam surfaces 20, 20, for a purpose hereinafter to be described.

The rods 11, 11 support the seal flap gumming die 6, projecting loosely through bushings 21, 21 provided by the head 12, as shown clearly in Figs. 4 and 7. On the upper ends of said rods are cap nuts 22, 22 that cooperate with nuts 23, 23 in holding said rods rigid with a connecting member or yoke 24, the latter having a central bearing portion 25 in which is disposed, head downward, a bolt 26. Said bolt passes through and has its head engaged with the arm 27 of a latch member 28, the latter being pivoted on a shaft 29, carried by head 12, and supporting at its ends the rollers 18. Latch member 28 provides a tooth or projection 30 for cooperation with a shouldered recess 31 in the upper surface of bar 4, whereby in the position of the parts shown in Figs. 3, 4 and 5, the head 12 is positively locked in its rear-most position, to retain the gumming die 6 in overlying relation to the seal flap of the blank, as shown in Fig. 9.

25 On the outer end of bar 4 is disposed a cam member 32 adapted to cooperate, in the manner hereinafter described, with the head of bolt 26, so as to elevate said bolt and thereby, through yoke 24 and connected rods 11, 11, 30 to relieve the pressure of the gumming die 6 on the stack of blanks. Such pressure is exerted, during the major portion of the gumming and wiping operations by springs 33, 33 that surround the reduced portions of the 35 rods 11, 11 within the bushings 21, 21, said springs acting against shoulders 34 of said rods to force the die 6 to the limit of its downward movement, as shown in Figs. 4 and 5. The operation of the mechanism as 40 above described is as follows:—

Starting with the parts in the positions shown in Fig. 3, with the dies 5, 5 and 6 at their extreme distances away from the stack of blanks 35, it will be clear that the initial 45 downward movement of the picker rod 3 is without effect upon the position of the parts until the die 6 strikes the stack of blanks. This is because of the fact that at the commencement of the movement the rolls 18 bear 50 against the vertical inner surfaces of overhanging members 19, as shown most clearly in Fig. 5, and also because of the fact that as the downward movement continues, bringing the rolls 18 opposite the inclined cam surfaces 20 of members 19, the latch member 28, 55 as shown most clearly in Fig. 6, retains the head 12 in its normal retracted position,—holding the rolls 18 out of contact with the cam surfaces 20.

60 The gumming die 6 makes contact with the stack of blanks slightly in advance of the gumming dies 5, 5. The downward movement of the picker necessary to bring the dies 5, 5 into contact therewith causes a slight 65 upward movement of the gumming die 6

against the force of springs 33, 33, as shown most clearly by a comparison of Figs. 4 and 7; this causes the rods 11, 11 to lift the yoke 24, and thereby, through the bolt 26, to raise the latch 28 so as to release the head 12, as shown in Fig. 8, at an instant when the dies 5, 5 are exerting their maximum pressure on the stack of blanks.

The release of the latch 28 makes the springs 17, 17 effective to force the head 12 75 outwardly, along the guideway afforded by bar 4, thus wiping the die 6 horizontally across the edge of the seal flap, as shown in Fig. 11, and procuring the thin and even spreading of the gum deposited thereon. 80 This horizontal movement of the head 12 carries the head of bolt 26 against the cam member 32, as shown in Fig. 10, and as the bolt head rides up the surface of said cam, the yoke 24 and rods 11, 11 are elevated slightly 85 so as to relieve the pressure of the die 6 as it gradually passes off the edge of the stack 35; otherwise, the extremely small area left in contact with said die at the end of the wiping movement, as indicated at 36, Fig. 90 11, would not suffice to withstand the pressure normally exerted by the springs 33. It is to be understood, of course, that during this wiping operation, the dies 5, 5 serve to 95 clamp the uppermost blank of the stack 35 against sidewise movement, so that wiping is accomplished without disturbing the correct position of said uppermost blank. Thereafter, the entire picker structure is 100 moved upwardly, carrying with it, by adhesion to the dies 5, 5 and 6, the topmost blank, which is stripped therefrom and conveyed to the folding station by the usual stripping plate and reciprocating carriage, not here 105 shown, since these devices form no part of the present invention. The upward movement of the picker structure brings the rolls 18 into contact with the stationary cam surfaces 20, and as said upward movement is continued, the head 12 is gradually retracted, 110 and simultaneously, the springs 33 are allowed to expand as the head of bolt 26 moves off of cam member 32. This releases the latch member so that when full retraction of the head 12 is effected, the tooth 30 is again 115 disposed against the shoulder 31, so that the parts are again in the position shown in Figs. 3, 4 and 5, ready to repeat the above described operation.

I claim,

1. In an envelope machine, a picker mechanism comprising a plurality of flap gumming dies adapted for movement in unison toward the blanks, one of said dies making contact with the blanks in advance of the others.
2. In an envelope machine, a picker mechanism comprising a plurality of flap gumming dies, one of said dies adapted to yield upon contact with the blanks, and means 130

responsive to the yielding of said die for procuring its traverse over the surface gummed thereby.

3. In an envelope machine, a picker mechanism comprising a plurality of flap gumming dies, one of said dies adapted to yield upon contact with the blanks, and means responsive to the yielding of said die for procuring its traverse over the surface 10 gummed thereby while the blank is held stationary by the other dies.

4. A picker mechanism for envelope machines and the like, comprising yielding and unyielding dies, the former adapted to move laterally while the blank is held stationary by the latter, and means for locking said 15 yieldable dies against lateral movement.

5. A picker mechanism for envelope machines and the like, comprising a set of dies 20 adapted for movement as a unitary structure into contact with the top blank of a stack, means responsive to said contact for procuring a wiping movement of one of said dies, and means responsive to the elevation 25 of said picker mechanism for returning said wiping die to normal position.

6. A picker mechanism for envelope machines and the like, comprising a plurality of dies, one adapted for wiping movement 30 when in contact with a blank, a latch for retaining said wiping die in its normal retracted position, and means for releasing said latch by the pressure of said die on said blank.

35 7. A picker mechanism for envelope machines and the like, comprising a plurality of dies, one adapted for wiping movement when in contact with a blank, a latch for

retaining said wiping die in its normal retracted position, means for releasing said 40 latch by the pressure of said die on said blank, and means operable by release of said latch for procuring the wiping movement of said die.

8. A picker mechanism for envelope machines and the like, comprising a plurality of dies, one adapted for wiping movement when in contact with a blank, a latch for retaining said wiping die in its normal retracted position, means for releasing said 45 latch by the pressure of said die on said blank, means operable by release of said latch for procuring the wiping movement of said die, and means responsive to said wiping movement for relieving the pressure of 50 said die on said blank.

9. A picker mechanism for envelope machines and the like, comprising rigid dies and a spring pressed die, a common support for all of said dies, by which they are moved 60 into contact with a stack of blanks, means responsive to the yielding of said spring-pressed die for procuring its traverse over the surface gummed thereby, means responsive to said traverse for relieving the spring 65 pressure on said die, and means responsive to the elevation of said picker mechanism for restoring said spring pressure and for returning said die to normal retracted position.
